UNITED STATES PATENT OFFICE

159,203

LUGGAGE CASE OR SIMILAR ARTICLE

Don W. Hawley, Geneva, Ill., assignor to Hawley Products Company, St. Charles, Ill., a corporation of Delaware

Application January 25, 1950, Serial No. 7,456

Term of patent 14 years

(Cl. D87—5)

To all whom it may concern:

Be it known that I, Don W. Hawley, a citizen of the United States, residing at Geneva, in the county of Kane and State of Illinois, have invented a new, original, and ornamental Design for a Luggage Case or Similar Article, of which the following is a specification, reference being had to the accompanying drawing, forming part thereof, in which:

Fig. 1 is a top perspective view of the luggage case or similar article embodying my new design;

Fig. 2 is a side perspective view of the luggage case or similar article; and

Fig. 3 is an end perspective view thereof.

I claim:

The ornamental design for a luggage case or similar article, substantially as shown.

DON W. HAWLEY.
